UNITED STATES PATENT OFFICE.

EZEKIEL K. DAVIS, OF NEW YORK, N. Y.

IMPROVEMENT IN LOOMS FOR WEAVING PILE FABRICS.

Specification forming part of Letters Patent No. 86,651, dated February 9, 1869.

To all whom it may concern:

Be it known that I, EZEKIEL K. DAVIS, of the city, county, and State of New York, have invented and produced an Improvement in Looms for Weaving Pile Fabrics, of which the following is a full, clear, and exact description, reference being had to the accompanying drawings making part of this specification:

This invention relates to a mechanism or device for working the wires in weaving pile fabrics, in which the wires are drawn from the cloth and inserted in the warp-shed in rotation; also, to an arrangement of the shuttle-box on one side of the loom, whereby it is caused to slide upon the lay of the loom instead of being firmly secured to the lay, as in ordinary looms; and, also, to an improved arrangement for working the cams that operate the heddle-frames of the several warps.

Figure 1 is a general plan of the improvements and parts of the loom to which they are attached. Fig. 2 is a front elevation of the same. Fig. 3 is an end elevation. Fig. 4 is a side elevation of the device for securing the wires during the process of drawing and inserting. Fig. 5 is a plan of section of said device. Fig. 6 is an end elevation of the same. Fig. 7 is a plan, showing the relative positions of sliding shuttle-box, slotted bar, and wire-box when the wire is being drawn, and the lay at the extreme forward point of its beat. Fig. 8 is a plan of the relative positions of sliding shuttle-box, slotted bar, and wire-box when the lay is thrown back and the wire being inserted in the shed.

Similar letters of reference in the various figures indicate like parts.

The parts of the loom shown in the drawings, and herein specified, form no part of my invention, but are simply shown to exhibit the connection of the improvement with the body of the loom.

The term "wire-motion" is commonly applied to the mechanism employed for drawing and inserting the wires; and when it occurs in this specification will have that application.

A is a slotted bar in which the wires slide, and by which they are guided during the process of drawing and inserting. The slotted bar A is supported by the arms *a a*, which are attached to the rocker-shaft *b*, which has

suitable bearings on the frame of the loom. The motion required to transfer the wire, after it is drawn, from the line of the cloth to the proper position for entering the shed is imparted to the slotted bar A by means of the cam B acting upon the lever *c*, which is secured at one end to the rocker-shaft *b*. The spiral spring *d* serves to hold the roller of the lever *c* in contact with the face of the cam B during regular action, and, in case of any obstruction to the backward motion of the slotted bar A, permits said bar to remain forward, and prevents breakage. The cam B is of such construction as to allow the bar A to remain stationary while the wire is being drawn from the cloth. This cam is secured to one end of shaft *e*, which is operated by suitable gearing connecting it with the driving pulley or gear. C C is a steel plate arranged to slide in and traverse the full length of the slotted bar A, and supports the hook *f*, spring *g*, lever *h*, spring *i*, and plate *j*, which securely hold the wire during the process of drawing and inserting. A section of the wire with a suitable head, *k*, is shown in Fig. 4; and it will be seen that the hook *f*, held in position by the spring *g*, secures the wire for the purpose of drawing, while the lever *h* held by the spring *i* presses against the lower edge of the wire-head *k* and holds it in its proper position in the slotted bar A. When the wire is being driven into the shed the plate *j* presses against the back of the wire head *k* for the purpose of driving. The traverse-motion required to draw and insert the wires is imparted to the steel plate C C and its connections by means of the traverse-cam D acting upon the lever E, which transmits the motion to the plate C C through the arm F, one end of which is secured to the lever E, the other to the plate C C. In order to support the end of the wire, when it is drawn, a pin, *l*, is inserted in the slotted bar A near the end next to the body of the loom, as this pin, should it remain at all times in the bar, would interfere with the passage of the plate C C when it is driven up to insert the wire. It is secured to one end of the long spring *m* on the side of the bar, and as the plate C C is moved forward to drive the wire a pin or stud, *n*, attached to said plate, comes in contact with the spring *m* at a point shown at *o* in Figs. 1, 2, 7, and 8,

presses it out sufficiently to remove the pin *l* from the slot in the bar *A*, and allows the plate to complete its forward motion without obstruction. When the plate *C C* is traversing backward, and drawing the wire, the stud *n* relieves the spring *m* at the point *o*, before mentioned, and the pin *l* enters the slot in the bar *A* in time to support the end of the wire as it comes from the cloth. The positions of the spring *m* and pin *l*, both when the plate *C C* and its connections are in position to seize a wire, and when the wire is being driven into the shed, are respectively shown in Figs. 7 and 8. *p p*, shown in Figs. 1, 7, and 8, represent the wires in the cloth or pile. *G* is the wire-box, so called, which holds the wire-heads in a proper position. *S* is a slot in the top of the wire-box *G*, into which the hook *f* of the plate *C C* drops to seize a wire as the bar *A* is brought forward for the purpose of receiving and drawing the wire. The plate *j* of the steel-plate *C C*, besides serving to push the wire in inserting, also presses against the heads of the wires in the box *G* when the bar *A* is returning from the line of inserting to that of drawing, and keeps them true, and in proper position to be seized in turn by the hook *f*. The position of the plate to accomplish the object is partially shown in Fig. 1. When the wire is driven by the plate *C C* and its connections as far into the shed as is required, its head is relieved from the clutch of the hook *f* and lever *h* by their being pressed against an attachment to the wire-box, and in the return of the bar *A* to the line of drawing they respectively pass over and under the wire-box *G* until they arrive at the slot *s*, where they seize upon the wire-head presented there, and hold it in the manner shown in Fig. 4 as long as is required to draw and insert the wire.

In the proper working of improved wire motions for pile fabrics it has been considered necessary to detach the shuttle-box from the lay on the side of the loom that the wires are drawn and inserted, in order to give the wire motion room for its operation.

A part of my improvement consists in so arranging the shuttle-box *H* as to slide upon the lay, so that when it is necessary to throw and receive the shuttle the box is in line with the race of the lay, the same as though it were secured to it, but when the lay is thrown forward to beat up the filling the box is not carried with it, but retarded in its motion sufficiently to give the wire motion free play. This is accomplished by grooving the lay transversely on the side required and fitting the shuttle-box *H* with tongues to work in the grooves. The box is secured to the arms *x x*, connecting with the rocker-shaft *t*, which has suitable bearings or supports at-

tached to the lay. The arm or lever *u* is secured at one end to the rocker-shaft *t*, and at the other end supports a stud and roller which work in the cam-path *J*, which is attached to the frame of the loom, as shown in Fig. 3. The cam-path *J* is of such peculiar construction as to cause the arm or lever *u*, through its connection with the rocker-shaft *t* and the lay, to allow the shuttle-box *H* to move with the lay long enough to throw and receive the shuttle, and then gradually retard its motion while the lay goes forward to complete its beat, and as the lay begins to recede, gradually increases the backward motion of the box until it is again in line with the race of the loom, when it works with the lay the same as though it were secured to it, until it again arrives at the point of retarding in the forward beat.

The common method of operating cams for working the heddle-frames for the several warps of pile-fabrics has been to secure the cams all to one shaft, and the different motions required are attained by the construction of the cams, either double or single, as the case requires.

My improvement consists in working the fine warp or cloth-making heddles by cams *K L*, driven by the compound bevel-gears *M N O R*, the cams *K L* being secured to the gear *O*, which revolves on the shaft *e* in an opposite direction to that of the shaft *e*, making one revolution to two of said shaft.

The cams *P Q* which operate the pile and stuffing warps are secured to the main shaft *e*, and thereby make two revolutions to one of the cams *K L*, and revolve in an opposite direction to said cams.

What I claim as my invention, and desire to secure by Letters Patent, is—

1. The slotted bar *A*, in combination with the plate *C C*, hook *f*, spring *g*, and spring *i*, lever *X*, and plate *j*, constructed and arranged substantially as described, and for the purpose set forth.

2. The pin *b*, spring *m*, and stud *n*, arranged and combined with the slotted bar *A*, for the purpose of supporting the wire while in process of drawing and inserting, substantially as described, and for the purpose specified.

3. The sliding shuttle-box *H*, combined with arms *X X*, rocker-shaft *t*, lever *u*, and cam-path *J*, substantially as described, for operating the shuttle-box.

4. The bevel-gears *M N O R*, arranged substantially as hereinbefore described, for the purpose specified, of operating the heddle-cams, as set forth.

EZEKIEL K. DAVIS.
